Patented Nov. 12, 1968

212,709

DISHWASHING BASKET

Louis Maslow, Huntsville Road, Dallas, Pa. 18612

Filed Jan. 17, 1968, Ser. No. 10,199

Term of patent 14 years

(Cl. D49—1)

FIG. 1

FIG. 2

FIG. 3

I claim:

The ornamental design for a dishwashing basket, substantially as shown.
